UNITED STATES PATENT OFFICE.

HARRY DOTY, OF EAST ORANGE, NEW JERSEY.

TELEPHONE CALL-INDEX.

No. 839,738.

Specification of Letters Patent.

Patented Dec. 25, 1906.

Application filed January 22, 1902. Serial No. 90,817.

To all whom it may concern.

Be it known that I, HARRY DOTY, a citizen of the United States, and a resident of East Orange, Essex county, New Jersey, have invented certain Improvements in Telephone Call - Indexes, of which the following is a specification.

My invention relates to telephone indexes or cards containing the numbers and names of telephone subscribers; and it consists of a suitable structure of this character applied directly to the telephone-transmitter, whereby a series of subscribers' numbers required for constant use are disposed at a point most convenient to the user of the telephone.

My invention is fully illustrated in the accompanying drawings, in which—

Figure 1 is a front elevation of a telephone-transmitter containing an index-card made and disposed in accordance with my invention, the mouthpiece of the transmitter being shown in section. Fig. 2 is a side elevation of the structure shown in Fig. 1. Fig. 3 is a sectional view of the telephone-index structure, taken on the line *a a*, Fig. 1; and Fig. 4 is a view similar to Fig. 1, illustrating a modified structure embodying my invention.

Telephone-transmitters are usually provided with number-plates which, as shown in the drawings, are located directly below the mouthpiece, and I arrange my improved index in such a way that said number-plate will not hide any of the material part of the same.

In the accompanying drawings, 1 represents the mouthpiece of the telephone-transmitter; 2, the casing containing the diaphragm; 3, a rotatable disk card fitting around an annular projection or shoulder 4, carried by the face of the diaphragm-casing and free to turn thereon, and 5 a disk card which fits against said projection or shoulder 4 and is held in fixed position with relation thereto by the mouthpiece 1, the latter being temporarily removed in order to fit both of said cards in place.

The fixed card 5 is provided with a radial opening 6, through which may be viewed the names of telephone subscribers contained on the under card 3, the numbers of which are displayed on the marginal edge of said card 3. This movable disk card may contain quite a series of telephone-numbers and names divided into sections which will contain certain portions of the alphabet, and all of such names may be successively viewed

through the radial opening of the fixed disk card by turning the movable disk card to the desired positions.

The fixed card may contain any desirable advertising matter. For instance, my device is intended as an advertising novelty, the fixed card to contain the name and telephone-number of a distributor who employs the device solely for advertising purposes, while the movable card contains blank spaces to receive other telephone-numbers with the names of subscribers most frequently called by the user.

In Figs. 2 and 3 I have shown in side and sectional elevation, respectively, the position of the fixed and movable disks with relation to the mouthpiece and diaphragm-casing of the telephone.

The disposition of the radial opening in the fixed card is not arbitrary, as it may be formed at the left - hand side of the card, as illustrated at 6^a in Fig. 4, instead of the right-hand side, as shown in Fig. 1. When arranged at the left-hand side of the fixed card, the position of the reference matter on the movable card will be reversed—that is to say, the margin of such card will contain the names of subscribers, while the numbers will show through the opening 6^a. In Fig. 1 of 85 the drawings the end of the opening 6 is closed by a portion 7 of the fixed card 5; but in some instances this end may be left open, as shown in Fig. 4.

Having thus described my invention, I claim and desire to secure by Letters Patent—

1. In a telephone call index or directory, the combination with the telephone transmitter and mouthpiece, of a circular card of stiff material having a central aperture fitting around the neck of the telephone-mouthpiece and disposed between said telephone-mouthpiece and the face of the transmitter, said card extending beyond the surface of the transmitter and being free to rotate with respect to the transmitter.

2. In a telephone call index or directory, the combination with the telephone transmitter and mouthpiece, of a circular card of stiff material having a central aperture fitting around the neck of the telephone-mouthpiece and secured between said telephone-mouthpiece and the face of the transmitter and a supplementary card underlying the fixed card and projecting beyond the edge of the same, said supplementary card having a

central aperture also fitting around the neck of the telephone-mouthpiece, and being free to rotate with respect to the transmitter, and said fixed card having a slot or opening 5 through which a portion of the supplementary card may be viewed.

3. In a device of the character described, the combination with the telephone transmitter and mouthpiece of a plate of stiff 10 flexible material having a circular aperture fitting around the neck of the telephone-mouthpiece and secured between said telephone-mouthpiece and the face of the transmitter, said plate extending beyond the surface 15 of the transmitter, substantially as described.

4. In a telephone call index or directory, the combination with the telephone transmitter and mouthpiece, of a circular card of 20 stiff material having a circular aperture fitting around the neck of the telephone-mouthpiece and secured between said telephone-mouthpiece and the face of the transmitter, said card extending beyond the surface of the 25 transmitter.

5. In a number and name card for telephones and in combination with the instrument proper, a front card having openings therein, and a second card carrying a series 30 of subscribers' numbers thereon arranged to be exposed to view through one of the openings in said front card and located against the instrument proper, said second card being held against removal by the front card and 35 the latter being clamped between the instrument and the mouthpiece of the transmitter.

6. In combination with a telephone-transmitter and its mouthpiece, a card through which the mouthpiece is passed, and a sec-

ond card having indicating matter thereon, 40 said second card being maintained by the first card about the mouthpiece and in front of the face-plate of the transmitter.

7. The combination of a telephone-transmitter, a fixed card carried thereby and having an opening, and a movable disk card also carried by said transmitter and having matter to be viewed through the opening of the fixed card, said movable card extending beyond the surface of the transmitter. 45

8. The combination of a telephone-transmitter, a fixed card carried thereby and having a radial opening, and a movable disk card also carried by said transmitter and having matter to be viewed through the radial opening of the fixed card, said movable card extending beyond the surface of the transmitter. 50

9. The combination of a telephone-transmitter, a fixed card carried thereby and having an opening; and a movable card also carried by the transmitter and disposed beneath the fixed card, said movable card being of greater diameter than the fixed card and having matter disposed at the periphery of 60 the same to be read in connection with the matter on said movable card viewed through the opening of the fixed card, said movable card extending beyond the surface of the transmitter. 70

In testimony whereof I have signed my name to this specification in the presence of two subscribing witnesses.

HARRY DOTY.
